FASTENER-DISTRIBUTING MECHANISM

William Thomas Buckingham Roberts, Leicester,
England, assignor to United Shoe Machinery
Corporation, Paterson, N. J., a corporation of
New Jersey

Application April 2, 1934, Serial No. 718,555
In Great Britain June 9, 1933

38 Claims. (Cl. 1—39.1)

This invention relates to fastener or like assorting and distributing mechanism and is particularly, but by no means exclusively, concerned with nail-assorting and distributing mechanism associated with machines for use in building heels 5 for boots or shoes or for attaching heels to boots or shoes during their manufacture.

The manufacture of heels and their attachment to boots or shoes at times require that nails of different length, and it may be also of thickness, be used to suit the particular height of heel being operated upon. In some instances a comparatively frequent change is called for, for example when small lots of work with heels of varying sizes are being dealt with by a single machine. Such a machine may be provided with mechanism by which nails are delivered from a mass in successive loads to the operating means. One form of nail-distributing mechanism of this character is described in the specifications of British Letters Patent Nos. 23,356 of 1904 and 17,708 of 1908 and in Letters Patent of the United States No. 1,119,793, Bingham et al., December 8, 1914. In such a mechanism, however, changing of the nails which are in the supply-receptacle or nail-drum and raceway for others of different length is somewhat inconvenient and occupies an undesirable amount of time. This drum is made in two sections, one being fixed to the frame of the mechanism and having secured to it a raceway down which the nails pass for delivery to the operating mechanism, and the other being rotatable to lift the contained nails and drop them on the raceway. When changing the 30 nails, the rotary drum is removed, the nails emptied, and the nails in the raceway moved up the raceway so that they fall from its upper end or are picked out by the operator. The rotary drum is customarily provided with a flange at that side from which the nails are emptied. This interferes with their discharge. If in changing the nails the thickness of the fresh nails is different from that of those previously used, it may be necessary to change the raceway for one 40 suitable for the fresh nails, and also to change the nail-receiver which takes the nails one by one from the end of the raceway, since the nail-receiving chambers in the nail-receiver may not be of suitable depth. If they are too deep a 50 second nail may pass from the end of the raceway partly into the chamber and prevent movement of the receiver. If they are not deep enough the endmost nail will not pass fully into the chamber and will again prevent movement of the receiver.

The present invention has among its several objects the provision, in a nail or like fastener-assorting and distributing mechanism of the kind referred to, of facilities for the speedy emptying of the nail-receptacle and the raceway, ready means for changing the raceway, and means for quickly adjusting the depths of the nail-chambers in the nail-receiver. 5

The above and other objects and the several features of the present invention will become apparent from a consideration of the following description, given by way of example, of a particular form of mechanism according to the present invention. 10

In the drawings, which show the present invention as applied to a heel-attaching machine, 15

Fig. 1 is an elevation of one embodiment of the improved mechanism;

Fig. 2 is an elevation, partly in section, of a portion of the mechanism viewed from the left 20 in Fig. 1;

Fig. 3 is a detail plan view of a plunger and its actuating lever shown in Fig. 2;

Fig. 4 is a side elevation to an enlarged scale of part of the mechanism shown in Fig. 1; 25

Fig. 5 is a detail in side elevation enlarged of the raceway-cover and its supporting means shown in Figs. 1 and 4;

Fig. 6 is an elevation of the raceway-cover and supporting means viewed in the direction of the arrow in Fig. 5; 30

Fig. 7 is a vertical section through the nail-counting and distributing mechanism shown in Fig. 4;

Fig. 8 is a section on the line VIII—VIII in Fig. 5; and 35

Fig. 9 is an elevation showing some of the parts inside the nail-drum.

The illustrated mechanism comprises a bracket 1 adapted to be fixed to the frame of the machine M with which the said mechanism is associated. This bracket carries nail-counting and distributing mechanism and its driving means similar, except as will hereinafter appear, to the mechanism shown in the specification of Patent No. 23,356 of 1904 previously referred to. The bracket 1 has mounted upon it a nail-receptacle provided with a rotatable section 15 and a normally stationary section 39. Fixed in the bracket 1 is a horizontal spindle 3, and carried by the spindle is a swinging bracket 5 which projects upwardly and has secured to it a forwardly extending block 7 having in its under face a groove which receives a tongue 9 on the bracket 1. This tongue and groove give support 40 45 50 55 60 65 70 75 80 85 90 95 100

to the bracket 5 against a tendency to tip lengthwise of the spindle 3. The upper end of the bracket 5 has rotatable in it a horizontal tubular shaft 11 positioned directly above the spindle. At 5 the front of the bracket 5 the shaft 11 has keyed to it a hand-wheel 13 by which it may be rotated, and at the rear of the bracket the shaft has rotatably mounted on it the part 15 of the nail-drum or receptacle, in which nails are placed 10 in bulk and by which they are lifted and dropped on a raceway 17. Down this raceway the nails travel to the separating and distributing mechanism. The part 15 of the drum has formed on its inner wall shelves which carry the nails up 15 and drop them on the raceway. This part of the drum has formed around its periphery a groove 18 to receive a belt 19, which also passes around a portion 21 of a double pulley 21 and 25 loosely mounted on a driving shaft 23 of the assorting 20 and distributing mechanism. A belt 27 passes around the pulley-portion 25 and around a pulley 28 on the continuously rotated driving shaft of the machine with which the assorting and distributing mechanism is associated, so that the 25 rotary drum is driven continuously instead of intermittently, as in the mechanism of British Patent No. 23,356 of 1904, for a purpose herein-after described.

Extending from the swinging bracket 5 is an 30 arm 29 which has secured in it a vertical pivot-pin 31. The axis of the pivot-pin 31 lies in the same plane as the rear face 33 of the rotary drum 15. Pivoted on the pin 31 is an L-shaped bracket 35 having at its upper end a bearing for a 35 horizontal shaft 37 which is coaxial with the shaft 11 on which the drum 15 rotates. The shaft 37 extends from the second and normally stationary part 39 of the double drum. Projecting from the interior face of the drum 39 is an arm 41 having secured to it a block 43 carrying a shelf 45, which directs toward the raceway 17 the nails raised by the drum 15 and dropped on said shelf. The block 43 has a boss 47 in the front face of which is a groove 49 (Figs. 40 2 and 9). This groove receives a tongue 51 on the rear end of the shaft 11 on which, as herein-before described, the drum 15 is mounted. If the shaft 11 is rotated by means of the hand-wheel 13, the stationary drum 39 is also rotated, for 45 a purpose herein-after described. The shaft 11 has passing axially through it a rod 53 rotatable by a hand-hold 55. The rod 53 at its rear end is threaded and is screwed into the block 43 to hold the adjacent faces 33 and 57 of the two 50 drums substantially in contact. When the rod 53 is released from the block 43, the drum 39 and the bracket 35 which carries it may be swung about the pivot pin 31 of said bracket so that access is readily obtained to the inside of the 55 drum without removing any parts of the mechanism. The lower part of the drum 39 is formed as indicated at 59, so that the nails in the drum tend to flow into the drum 15. The upper part of the drum 39 is formed so that, when turned 60 through substantially 180°, the nails flow from both sections toward what is then the bottom of the drum 39. The latter has formed in its outer peripheral wall an opening through which the contained nails are discharged. This opening is 65 normally closed by a hinged lid 61, which when the section 39 is rotated falls open. The inner face of the lid is shaped so when said lid is open it directs the nails flowing from the hopper into a chute 63 (Fig. 1). The drum 39 after it has 70 been rotated from its normal operating position 75

is held in this position by a spring-plunger 65 mounted in the bracket 35 and engaging a recess 67 in a boss 69 on the outer wall of the section 39. The boss is so shaped on its rear face that as the drum 39 is rotated it pushes back the 5 spring-plunger 65 until the recess 67 is in alignment with the plunger, when the latter snaps into the recess. A face 71 on the boss 69 engages the side of the plunger 65 when said plunger and the recess come into alignment and prevents the 10 drum 39 from being turned so far that the recess would pass the plunger. A hand-lever 73 pivoted on the bracket 35 is connected to the plunger 65, so that said plunger may be withdrawn from the recess when it is desired to re- 15 turn the drum 39 to its operating position.

The nail-delivering raceway 17 is secured to the drum 39. At its upper end, it rests on the bottom of a recess 75 (Fig. 2) formed in the arm 41, hereinbefore described as extending from the 20 inner face of the drum 39, and the sides of the raceway are engaged by the sides of the recess. The raceway is held in position by a plunger 77 which is slidably mounted in and axially of the shaft 37 and enters an opening in one side of 25 the raceway. The plunger extends outside the shaft 37 and has a pair of flanges 79 (Fig. 3) between which is arranged the rounded forked end of a lever 81 pivoted on the arm 35. The lever 81 is acted upon by a spring-plunger 83, 30 carried in the arm 35, to hold the plunger 77 in engagement with the opening in the raceway. The raceway, where it emerges from the drum 39, passes through a recess formed partly in the front wall of said drum 39 and partly in a projection 35 85 (Fig. 5) on this part of the drum. The raceway is supported on the lower face of the recess and has secured to one side a block 87 which enters a recess 89 in the projection. By this means the raceway is prevented from moving 40 upwardly or downwardly relatively to the drum. When the plunger 77 has been withdrawn from the opening in the raceway, after the drum and raceway have been rotated as hereinbefore described, the raceway may be drawn lengthwise 45 out of the drum. The lower end of the raceway 17 is seated in a recess in a bearing 91 for the spindle 187 of a rotatable nail-receiver 143. This receiver has at its inner face a series of radial grooves A² (Fig. 7) successively co-operating with 50 the end of the raceway to remove nails therefrom. The raceway has secured to one side near its lower end a small block 93, which engages at 55 90 the end of one wall of the recess. The end of the block 93 has a tooth 92, which enters a recess 94 in the inner face of the wall, as shown in Fig. 4, to position the lower end of the raceway both lengthwise and heightwise. The interengaging portions of the block 93 and wall are disengaged, by means now to be described, before the drum 39 60 and raceway 17 are rotated about the axis of the drum to empty the drum and raceway. The bracket 5, hereinbefore described as supporting the drum, has mounted on it about midway between the axes of the spindle 3 and the shaft 11 65 and in the same plane as these axes, a cam-roll 95 which enters a cam-groove 97 in an arm 99 secured on a stud 101 parallel to the pivotal axis of the bracket 5 and rotatably mounted in the bracket 1. When the raceway 17 is in operating 70 position, the cam and cam-roll lock the bracket 5 against movement about the spindle 3 and press the block 93 on the raceway against the end of the wall of the bearing 91. Also secured on the said stud 101 is a second arm or hand-lever 103 75

by which the stud 101 and cam-arm 99 may be rotated. When the cam-arm 99 is thus turned, the bracket 5 and with it the double drum and raceway are moved about the spindle 3 of the bracket, the lower end of the raceway moving along the bottom face of the recess in the bearing 91 in a direction to disengage the tooth 92 on the block 93 from the recess 94 in the bearing. The drum and raceway may then be rotated by means 10 of the hand-wheel 13 about the axis of the shaft 11 to empty the nails from the drum. During this movement, the opening in the drum passes over the chute 63, hereinbefore referred to, which is secured to the bracket 35. This chute 63 at 15 its upper end is flared and passes part way around the drum 39 so that as the latter is being rotated and the hinged lid 61 opens any nails which fall out of the drum drop into the chute. The lower end 105 of the chute is cylindrical and 20 enters the enlarged upper end of a tube 107. The lower end of the tube enters a funnel 109 carried by a bracket 111, to which the tube 107 is secured and which is mounted on the frame of the heel-attaching machine. The opening at the 25 lower end of the funnel is normally covered by a spring-controlled lever 113 pivoted on the bracket 111.

Beneath the bracket 111 is arranged a carrier 115 for a number of receptacles 117, any one of 30 which may be moved beneath the opening at the lower end of the funnel 109 by moving the carrier along a fixed guide 119. The carrier may be secured in position by a screw 121 which clamps the carrier to the guide. When the nails have 35 been emptied from the drum and raceway into the tube 107, the lever 113 may be swung away from the opening in the funnel to allow the nails to fall into one of the receptacles 117, which may then, if desired, be readily removed and the nails 40 emptied from it.

To prevent the nails in the raceway 17 from passing out of its lower end when the raceway is withdrawn from the bearing 91, a latch 123 (Fig. 4) is provided which at that time closes the 45 lower end of the raceway. The latch is pivoted at 125 to a bracket 127 secured to the side of the raceway opposite that to which the block 93 is secured. The pivot 125 extends in a direction across the raceway and is positioned so that the 50 hook-shaped end 129 of the latch moves about the pivot substantially parallel to the end of the raceway. The latch is pressed down by a spring-plunger 131 mounted in the bracket 127. When the raceway is in its operative position the latch 55 is raised so that its hooked end is above the lower end of the raceway. The latch 123 is held in this raised position by an arm 133 which engages the under side of the latch 123, this arm being angularly adjustable about a stud 135 rotatably mounted in the main bracket 1 of the nail-assorting and distributing mechanism. This stud has secured on it a second arm 137, the outer end of which is arranged to be engaged by a cam 139 formed on the cam-arm 99, which swings the 60 bracket 5 about its spindle 3. A hub of the arm 133 has extending through it above and below its stud 135 two screws 141, by which the arm may be adjusted about its pivot in its angular relation to the arm 137. By this means, the end 129 65 of the latch 123 may be set relatively to the upper face of the raceway, so that when the latch is in its raised position the nails will pass beneath it. When the cam member 99 is rotated to swing the bracket 5 about its spindle 3, the cam 139 frees 70 the arm 137, so the end 129 of the latch is pressed 75

down by the spring plunger 131 before the raceway begins to move away from the bearing 91 and from the nail-receiver 143. The nails are thus retained against discharge from the raceway. As said raceway continues to move away from the bearing 91 and receiver 143, a screw 130 adjustably carried in the latch rides up a cam 132 (Fig. 7) secured to the bearing 91 and thereby raises the end 129 of the latch 123 slightly above the nail in the receiver, which it might otherwise displace. Consequently, this movement of the latch does not drag the nail out of the receiver. On the other hand, this slight raising of the end 129 of the latch is not sufficient to allow the endmost nail in the raceway to be discharged therefrom. As the raceway continues to be moved away from the receiver, the screw 130 rides along the cam 132 with the end 129 of the latch in engagement with the endmost nail in the raceway. As the raceway is returned to operating position, the screw 130 slides down the cam 132 and the end 129 of the latch engages the nail in the receiver after the raceway has been returned to its operative position. Then the latch 123 is raised above the raceway by the cam 139 as hereinbefore described.

A cover 147 extends along the whole length of the raceway 17 and is secured to a bracket 149 which is pivotally mounted on a horizontal stud 151 extending across the raceway. The stud 151 is secured in a slide 153 and is arranged above the raceway and substantially above the upper end of the cover, so said cover can be swung upwardly to expose the raceway. The slide 153 is adjustably mounted on the drum 39 and is secured by a screw 155 passing through a slot 157 (Fig. 6) in the slide and threaded into the drum. An eccentric sleeve 159 (Fig. 5) surrounds the screw 155 and engages the upper and lower walls of the slot. The sleeve has on it a knurled head 161 by which it may be rotated to adjust the slide 153, bracket 149 and raceway-cover 147 toward or from the raceway to suit the height of the heads of the nails in the raceway. The eccentric 159 and slide 153 are clamped in position 45 on the drum 39 by the screw 155 passing through the sleeve. The bracket 149 covers an opening in the drum 39, through which opening, when the bracket 149 is swung upwardly, access may be gained to the upper end of the raceway 17 50 within the drum to clear or remove obstructions. The bracket 149 is held in position to close the opening in the drum by a spring-plunger 163 mounted in the projection 85 on the drum 39. This plunger engages a face 165 on a part 167 55 of the bracket 149 and may be pulled down when it is desired to swing the bracket and raceway-cover upwardly. A thin plate 169 is secured to the drum 39 and forms a stop against which the part 167 of the bracket 149 abuts.

The pivot 151 of the bracket 149 has rotatably mounted on it a nail-clearer 171, the lower face of which is curved about the axis of the pivot and has formed in it a groove 173 (Fig. 5) to allow the heads of the nails to pass beneath it. The 65 lower face of the nail-clearer is only just above the upper face of the raceway and its end extends into the drum between the plate 169 and the stationary drum 39. The clearer 171 has mounted on it a cam-roll 175 arranged to be engaged 70 by cams formed on the rotary drum 15 against which it is held by a spring 177 connected to the clearer 171 and to the bracket 149. Each cam is so shaped that the nail-clearer is first swung outwardly and then sharply back to kick off any 75

misplaced nails lying on the raceway just inside the drum. The upper end of the raceway-cover 147 is shaped so that it extends as far as possible into the groove 173 in the lower face of the nail-clearer to prevent nails from being jammed against the end of the raceway-cover.

If a change in the thickness of the nails is made, it may be desirable to change the nail-receiver 143 to provide nail-receiving grooves deep enough to properly receive the nails and avoid interference with the raceway as the receiver rotates. When a change in the thickness of the nails used has heretofore been made, it has been necessary to change the nail-receiver for one having nail-receiving grooves of suitable depth, and this change could not readily be accomplished. According to the present invention, the nail-receiving chambers or grooves may be cut through from one side to the other of the nail-receiver, and the face of said receiver adjacent its driving ratchet-wheel 179 (Fig. 4) has a boss 181 (Fig. 7). Mounted on the boss 181 is a disc 183 having projections 185 which enter the nail-receiving chambers A² in the nail-receiver and form the bottoms of the grooves. The receiver is carried by a shaft 187 bored axially and having mounted in it a spindle 189. The receiver is secured to the shaft by a taper pin 191, which passes through said shaft and through a slot in 30 and extending lengthwise of an enlargement of the spindle. The disc 183 is secured to the spindle by a pin 193. This pin 193 passes through a recess in the boss 181 on the nail-receiver and through a slot 195 formed in and extending lengthwise of the shaft 187. When the spindle 189 is adjusted axially, the disc 183 is moved along the shaft relatively to the nail-receiver. The spindle is screw-threaded at 197, and the bore in the shaft has rotatable in it a threaded sleeve 199 engaging the threaded portion of the spindle. The sleeve has about its periphery a groove 201 engaged by a pin 203 secured in the shaft 187 to prevent the sleeve from moving lengthwise of the shaft. The sleeve has on its outer end a knurled head by which it may be rotated to adjust the spindle 189 axially. The movement of the disc 183 by the adjustment above described is limited, on the one hand, by the nail-receiver 143 and, on the other hand, by the driving ratchet-wheel 179. The amount of possible adjustment of the disc is about one thirty-second of an inch, which is sufficient to allow for the difference in thickness between the thinnest and thickest nail usually dealt with by the mechanism.

Having described my invention, what I claim as new and desire to secure by Letters Patent of the United States is:

1. In a fastener-distributor, a fastener-receptacle having a rotatable section and a normally stationary section furnishing together opposite portions of an enclosure for the fasteners, the stationary section being provided with a discharge-opening, and means arranged to rotate the stationary section from its normal position to discharge contained fasteners through the opening.

2. In a fastener-distributor, a fastener-receptacle having a rotatable section and a normally stationary section provided with a discharge-opening, and means extending through the rotatable section and arranged to rotate the stationary section to discharge contained fasteners through the opening.

3. In a fastener-distributor, a fastener-receptacle having a rotatable section and a normally

stationary section provided with a discharge-opening, a closure for the opening, and means arranged to rotate the stationary section to discharge contained fasteners through the opening, the closure freeing the opening in the discharging position of the section and serving as a chute for the fasteners.

4. In a fastener-distributor, a fastener-receptacle having a rotatable section and a normally stationary section provided with a discharge-opening, means arranged to rotate the stationary section to discharge contained fasteners through the opening, and means into co-operation with which the stationary section is movable for temporarily locking said stationary section in the discharging position.

5. In a nail-distributor, a nail-drum having a rotatable section and a normally stationary section furnishing together opposite portions of an enclosure for the fasteners, the stationary section being provided at its upper portion with an opening, and means arranged to rotate the normally stationary section about the axis of the rotatable section to permit the discharge of the contained nails through the opening.

6. In a nail-distributor, a nail-drum having a rotatable section and a normally stationary section provided at its upper portion with an opening, a shaft about which the rotatable section turns, said shaft engaging the normally stationary section to cause its rotation, and means arranged to turn the shaft through substantially 180°.

7. In a nail-distributor, a nail-drum having a rotatable section and a normally stationary section provided at its upper portion with an opening, a shaft about which the rotatable section turns, said shaft engaging the normally stationary section to cause its rotation, means arranged to turn the shaft, and a latch for temporarily retaining the section in the position to which it is turned by the shaft.

8. In a nail-distributor, a nail-drum having a rotatable section and a normally stationary section provided at its upper portion with an opening, a cover for the opening hinged upon the stationary section, and means arranged to rotate said stationary section about the axis of the rotatable section to permit the cover to swing away from the opening and the nails to be delivered upon said cover.

9. In a fastener-distributor, a fastener-receptacle having a rotatable section and a normally stationary section, a mounting for the stationary section permitting it to be moved away from the rotatable section, and means extending through the rotatable section and engaging the stationary section to releasably retain said stationary section in its normal operating position.

10. In a fastener-distributor, a fastener-receptacle having a rotatable section and a normally stationary section, a mounting for the stationary section permitting it to be moved away from the rotatable section, a shaft about which the rotatable section turns, and a rod extending through the shaft and having threaded engagement with the stationary section.

11. In a nail-distributor, a nail-drum having a rotatable section and a normally stationary section provided at its upper portion with an opening, a tubular shaft about which the rotatable section turns, said shaft engaging the normally stationary section to cause its rotation, means arranged to turn the shaft, and a rod extending through the shaft and engaging the stationary section.

12. In a fastener-distributor, a fastener-receptacle having a rotatable section and a normally stationary section, and a mounting for the receptacle permitting both sections to be moved together, said mounting being provided with a portion movable to separate the stationary section from the rotatable section. 5
13. In a nail-distributor, a frame, a bracket pivoted upon the frame, a nail-drum-section rotatable upon the pivoted bracket, a bracket arranged to oscillate upon the pivoted bracket, and a nail-drum-section mounted upon the oscillatory bracket and movable thereby into and out of active co-operation with the rotatable section. 10
14. In a fastener-distributor, a fastener-receptacle having a rotatable section and a normally stationary section, a mounting for the receptacle permitting both sections to be moved together, said mounting being provided with a portion movable to separate the stationary section from the rotatable section, and means movable upon the mounting whereby the stationary section may be turned from its normal position. 15
15. In a nail-distributor, a frame, a bracket pivoted upon the frame, a shaft rotatable in the bracket, a nail-drum-section rotatable upon the shaft, a bracket arranged to oscillate upon the pivoted bracket, and a normally stationary nail-drum-section mounted upon the oscillatory bracket, the shaft engaging the last-mentioned section to turn it from its normal position. 20
16. In a nail-distributor, a frame, a bracket pivoted upon the frame, a tubular shaft rotatable in the bracket, a nail-drum-section rotatable upon the shaft, a bracket arranged to oscillate upon the pivoted bracket, a normally stationary nail-drum-section mounted upon the oscillatory bracket, the shaft engaging the last-mentioned section to turn it from its normal position, and a rod extending through the shaft and releasably engaging said last-mentioned section. 25
17. In a fastener-distributor, a fastener-receptacle having a section stationary during the normal operation of the distributor but mounted for rotation to permit the fasteners to be emptied, a raceway carried by said section, means engaging the raceway to prevent displacement in the direction of rotation of the section, and means arranged to move the section transversely of the axis of rotation to disengage the raceway from the engaging means. 30
18. In a fastener-distributor, a fastener-receptacle having a section stationary during the normal operation of the distributor but mounted for rotation to permit the fasteners to be emptied, a raceway carried by said section, means engaging the raceway to prevent displacement in the direction of rotation of the section, and means arranged to move the section transversely of the axis of rotation to disengage the raceway from the positioning means, and means arranged to rotate the section and raceway together. 35
19. In a nail-distributor, a frame, a bracket pivoted thereon, a nail-drum mounted upon the bracket, a cam device movable to turn the bracket upon its pivot, and retaining means from which the nail-drum is freed by such movement. 40
20. In a nail-distributor, a frame, a bracket pivoted thereon, a nail-drum mounted upon the bracket, and a cam device having a slot which at one extremity retains the bracket during the operation of the distributor in its normal position and between its extremities turns the bracket on its pivot. 45
21. In a nail-distributor, a frame, a bracket pivoted thereon, a nail-drum mounted upon the bracket, and a lever fulcrumed upon the frame and provided with a cam-slot, there being a projection from the bracket entering the slot. 50
22. In a nail-distributor, a frame, a bracket pivoted thereon, a nail-drum mounted upon the bracket, a raceway carried by the nail-drum, positioning means engaging the raceway, and a cam device arranged to turn the bracket upon its pivot and disengage the raceway from the positioning means. 55
23. In a fastener-distributor, a movable fastener-receptacle, a raceway carried by the receptacle, a movable fastener-retaining member co-operating with the raceway, and means movable to both move the receptacle and permit movement of the retaining member. 60
24. In a fastener-distributor, a fastener-receptacle, a raceway receiving fasteners therefrom, a movable fastener-retaining member co-operating with the raceway, and means movable to produce movement of the raceway, the movement of said means permitting the member to assume its fastener-retaining position. 65
25. In a fastener-distributor, a fastener-receptacle, a movable raceway receiving fasteners therefrom, a fastener-receiver to which the raceway delivers, a fastener-retaining member movable into engagement with a fastener in the receiver and at the end of the raceway, and means arranged to cause the movement of the retaining member with the raceway in fastener-retaining relation while freeing it from the fastener in the receiver. 70
26. In a nail-distributor, a movable nail-drum, a raceway carried by the drum, a movable retaining member for nails in the raceway, and a lever for moving the drum, said lever having a portion for controlling the retaining member. 75
27. In a nail-distributor, a movable nail-drum, a raceway carried by the drum, a movable retaining member for nails in the raceway, a lever for moving the drum, said lever having a portion for controlling the retaining member, and means fixed in position relatively to the raceway for controlling the retaining member. 80
28. In a nail-distributor, a movable nail-drum, a raceway carried by the drum, a movable retaining member for nails in the raceway, a lever engaging the retaining member, and a lever having a portion for moving the receptacle and a portion acting upon the lever of the retaining member. 85
29. In a nail-distributor, a movable nail-drum, a raceway carried by the drum, a movable retaining member for nails in the raceway, and a lever having a cam for moving the drum and a cam holding the member normally inactive and releasing said member to permit it to assume its nail-retaining position. 90
30. In a nail-distributor, a movable nail-drum, a raceway carried by the drum, a movable retaining member for nails in the raceway, a lever having a cam for moving the drum and a cam holding the member normally inactive and releasing said member to permit it to assume its nail-retaining position, and a cam in contact with which the retaining member is moved. 95
31. In a fastener-distributor, a movable fastener-receptacle, a raceway carried by the receptacle and being movable with and removable therefrom, and a member movable upon the receptacle to separably lock the raceway thereto. 100
32. In a nail-distributor, a nail-receptacle mounted to turn about an axis, a raceway car- 75

ried by the receptacle and being removable therefrom, and a latch for the raceway movable axially of the receptacle.

33. In a fastener-distributor, a raceway, a movable receiver having a nail-holding recess co-operating with the raceway, said recess having a movable wall, and means arranged to move said recess-wall and to retain it in different adjusted positions.

10 34. In a fastener-distributor, a raceway, a movable receiver having a nail-holding slot, a member movable in the slot toward and from the end of the raceway, and means arranged to retain the member at different distances from the race-

15 way.

35. In a nail-distributor, a raceway, a rotatable member provided with a series of nail-holding slots co-operating with the raceway, a second member having projections extending into the 20 slots, and means arranged to move one of the members toward and from the other.

36. In a nail-distributor, a raceway, a shaft, a disc fast upon the shaft and being provided with

a series of nail-holding slots co-operating with the raceway, and a disc movable longitudinally of the shaft and having projections extending into the slots.

37. In a nail-distributor, a raceway, a tubular 5 shaft rotatable in proximity to the raceway, a disc fast upon the shaft and provided with a series of nail-holding slots co-operating with the raceway, a second disc movable longitudinally of the shaft and having projections extending into the 10 slots, and means extending through the shaft for moving the second disc.

38. In a nail-distributor, a raceway, a tubular shaft rotatable in proximity to the raceway, a disc fast upon the shaft and provided with a 15 series of nail-holding slots co-operating with the raceway, a second disc movable longitudinally of the shaft and having projections extending into the slots, and a threaded spindle passing through the shaft, and a sleeve rotatable in the shaft and 20 being threaded to engage the spindle.

WILLIAM THOMAS BUCKINGHAM ROBERTS.
